UNITED STATES PATENT OFFICE.

HENRY C. KIESELBACH, OF BROOKLYN, NEW YORK; A. LAURA KIESELBACH AND HENRY A. KIESELBACH EXECUTORS OF SAID HENRY C. KIESELBACH, DECEASED.

MIXING CONTAINER.

Application filed August 3, 1936. Serial No. 126,836.

This invention relates to agitating and mixing in general, and resides in certain improvements in agitating and mixing-containers for such compound liquids as paints, 5 enamels and the like.

Paints, enamels, and other compound liquids exhibit a well-known tendency to precipitate out the pigments, mineral ingredients, or other solid matter held in a suspended condition therein, if their containers are left in storage long enough. It is imperative, however, that when it is applied to the surface to be treated, the liquid have a uniform consistency, and that each cubic inch 15 thereof contain the same quantity of pigment as every other, else the protective and decorative purpose of the painting will not be accomplished at all.

At present, paints, enamels, and the like, 20 upon receipt from storage or from the manufacturer, usually have to be prepared for use by stirring and mixing by means of a stick or paddle, which serves the purpose but poorly, particularly in loosening the solid matter 25 from the bottom of the can and mixing it with the base liquid. Consequently, also, a large amount of paint or enamel, as well as time, are invariably wasted, and, what is more important, the resulting so-called mixture is not uniform and does not contain an 30 adequate quantity of pigment.

I am aware that it has been proposed to provide containers in which liquids may be mechanically agitated and mixed, but such containers have been found to be not susceptible 35 of successful and economical manufacture, and the bulk of the paint or varnish used today is sold in containers having no provision for mixing or stirring.

It is a primary object of the present invention to provide a container for paints, 40 enamels, and the like which shall have a self-contained mixer designed to effect thorough mixing of the paint, and so combined with the container as to render the whole of such a low production cost that it may be used for the 45 packaging of the smaller quantities of paints without raising the retail price appreciably above that of non-mixing containers.

A particular object of the present invention is to provide a container having an improved mixing element, for example, one 50 which can operate to screw into the more or less coagulated layer of pigment at the bottom of the container when revolved in one

direction to enter the layer, and to lift and distribute this pigment evenly throughout the base liquid when revolved in another direction, at the same time scraping the bottom and sides of the can clear of the adhering pigment in order to perfect the mixture. 60

A further object of the present invention is to provide a mixing container, which upon its receipt from storage, can be operated to mix its contents, then opened, and later used, 65 without the employment of implements other than those actually constituting a part of the mixing container itself.

The invention will be described in connection with the accompanying drawings, which 70 illustrate a preferred embodiment and modifications thereof. In these drawings,

Fig. 1 is a vertical, central, sectional view, 75 partly in elevation, of one of the embodiments of the present invention;

Fig. 2 is a top plan view of the mixing container;

Fig. 3 is a sectional view along line 3—3 of Fig. 1, sighting in the direction of the arrows; 80

Fig. 4 is a sectional view along line 4—4 of Fig. 3, sighting in the direction of the arrows;

Fig. 5 is a detail view of upper portions of the present invention with certain of its elements in one position; 85

Fig. 6 is a detail view of other upper portions of the present invention, with these elements in another position;

Fig. 7 is a vertical, central, sectional view of an advantageous modification of the present invention, with part of the container 90 broken away for convenience;

Fig. 8 is a fragmentary top plan view of the modification shown in Fig. 7;

Fig. 9 is a top plan view of the modification 95 shown in Fig. 7 with one of the elements in another position;

Fig. 10 is a vertical, central, sectional view of a still further advantageous modification of the present invention, and 100

Fig. 11 is a vertical, central, sectional view of a further advantageous modification of the present invention, with part of the container broken away for convenience. 105

Referring now more in detail to the drawings by numeral, an advantageous embodiment of the invention is shown in Fig. 1 in its shipping or storage condition, and comprises a container-body or paint-can 1, having a detachable closure 2 of any suitable type, 110

here shown as the so-called "friction-top" type, the closure having a welltop or having a depression therein, as shown. This closure is provided with a small central aperture or bearing hole 13 of a sufficient size to permit a vertically extending metal rod or carrier-shaft 4 to project through the opening. A cap-nut 3 screws down on the screw-post 14 against a washer 11, and hence the cap-nut 3 and the closure 2 constitute the container a fluid-tight receptacle when these parts are thus arranged, and thus all disengageable parts are secured against knocking loose; or loss during shipment, or stacking, 15 or storage.

The upper end of the shaft 4 is screw-threaded as at 6; and the lower end carries an agitator head 5, a typical form of which is shown in Fig. 3 as comprising a hub 15 from which radiate several screw-blades or propeller vanes 12. These screw-blades or vanes 12 are connected at their outer ends by a ring or rim 16.

The blades or vanes 12 are preferably not more than four in number and lie at an angle of not less than about 30° , and not more than about 60° with the bottom of the container, to prevent sediment embedding them tightly in the bottom, yet at the same time not detracting from the effectiveness of the spiral-mixing action by being so inclined, and have their lower edges in scraping contact with the base of the container, and the ring or circular brace 16 preferably but not necessarily in contact with the side-walls, as shown most clearly in Fig. 4 and Fig. 10 in order to make it possible for the agitator-head to be screwed into the layer of pigment, when revolved, say clockwise, and to lift and thoroughly distribute the pigment when revolved in the other direction, and to also present to the usual layer of precipitated pigment accumulated at the bottom of the container, a sufficient number of cutting and scraping and grinding edges in order to effectuate thorough mixing of the paint. This screw-pump agitator-head causes the lower layers to ascend in copious quantities, but to descend in an ever-decreasing shower, as the pigment will naturally go into a suspended state in falling through the emulsifiant or base oil. Complete distribution of the pigment throughout the base oil is thus secured. Even after the container and contents have been standing for some time, and the detachable elements are removed from the container to permit the insertion of the painter's brush, though the contents be not mixed before so doing, nevertheless none of the sediment forming in the bottom of the can will be lifted out on the agitator-head itself, because of the inclination of the vanes or blades, which are near enough to vertical to shed off the bottom layer of pigment therefrom as the head is lifted up out of the can.

The agitator-head 5 is agitated while resting on the bottom of the container, and in close contact therewith, by means of forces applied to the combined container-opener and agitator-crank 7 when attached to the end of the shaft 4 as shown in Fig. 5. As shown in Figs. 2 and 5, this element 7 is a specially formed member, being substantially a ring with ends extended and recurved, and is constructed to rest, when the container is being shipped or stored, on its flat bottom side 17 on the top of the closure 2 around the cap-screw 3, and locked thereon, thus constituting the mixing container a unitary, rigid structure. This member 7 is hence protected from accidental displacement, and can be removed from its locked position only by the application of a horizontal force at one of its ends, or by a direct upward pull. The member 7 is actually a continuation of the shaft 4 and is a part thereof, and is constructed to be secured to the shaft 4 by means of the threads 9 and 6 as shown in Fig. 5. When so joined, it then functions as a crank handle for the agitator-shaft 4 and enables the agitator-head 5 to be rotated or oscillated in a horizontal plane, or lifted in a vertical plane while being oscillated, or to have imparted to it, any combination of these movements, successively or simultaneously, to aid the scraping, grinding, and screw-pump action of the agitator-head in effectuating thorough mixing and preparing of the contents of the container.

Upon completion of a reasonable amount of agitating, and when it is deemed that the contents of the can have been properly mixed, —the can remaining unopened from the moment of its purchase, during agitation, and until the brush is ready to be inserted into the container or the liquid poured out,—the agitator-shaft 4 with the blade-head 5 can be drawn up by the member 7, until the blade-head 5 is in juxtaposition with the closure 2, whereupon the member 7 can be rotated until one of the blades 12 passes between the jaws of the catch or support 10, whereby the shaft 4 and its head 5 are supported by the closure until the handle 7 is turned back through an equal and opposite horizontal angle to disengage the blade 12 from the catch 10 in order to lower it into the bottom of the container.

When in the position shown in Fig. 6, the member 7 can be removed simply and quickly with one hand by applying torque to it opposite in direction to that necessary to screw it on. This operation can be effected with one hand because the vertical part of the catch 10 will prevent rotation of the head 5 for more than one sector thereof, no matter whether the screw threads 6 be left or right-handed, and the horizontal part of the catch 10 will obviate the necessity of holding up the shaft by hand.

When the member 7 is removed, the wedge-shaped end 8 is ready to be inserted between the closure 2 and the container-body at any point on the joint thereof, and the member 7 elevated to loosen the closure 2, whereupon the closure may be lifted off by the shaft 4, and resting on the blade-head 5, whereby there occurs no splashing or waste of the contents and no soiling of the operator or the surroundings, and whereby ready insertion and withdrawal of a paint brush is made possible without further manipulations, as the interior of the container is then occupied only by the liquid compound, having no obstructions whatsoever therein; or alternatively, the mixed contents can readily be poured out.

In Figs. 7, 8 and 9 is shown a modified container, the change lying chiefly in the agitator-operating, closure-removing means, comprising variations not only in the member 7^a, but in the member 4^a as well. This modification contemplates a bend or goose-neck 41 at the upper end of the agitator-shaft 4^a, having a head 5 attached thereto in any suitable manner the end of the shaft being first thinned to a sufficient size to form a tenon capable of fitting through and engaging with a complementary mortise or aperture 42 in the extended end 43 of the member 7^a of the shaft 4^a. This member 7^a is substantially a ring in shape, and has a notch 44 for engaging with a tit or lug 45 on the surface of the cap-screw 3 in order to lock the section 7^a against the cap-nut for shipping, stacking, and storage, and thus the section 7^a also constitutes a wrench for unscrewing the cap-nut, as well as a crank-handle for the agitator and a closure-remover. The main purpose of this modification is to so decrease the cost of manufacture, without removing any of the novelties and advantages of the present invention, that the invention will be adapted for commercial needs.

In Fig. 10 is shown a mixer-element or agitator usable in containers of different sizes, and intended to be made independently of any particular container, the main feature of this modification being that it adapts the novel features of the agitator of the present invention to use with any shape or style of container. This modification comprises an agitator-head or stirrer 5 attached in any suitable manner to a vertical rod or shaft 4^b as shown in Fig. 10, which extends sufficiently far above the top of the container with which it is there being used as to enable the operator to complete the mixing of the contents efficiently and neatly by grasping it and operating the agitator. This shaft is bent at its end to a right angle handle 51 as shown, and the extremity of this handle is wedge-shaped to serve as an opener, as hereinbefore described. By means of this modification, the improved and advantageous screw pump agitator-head can be placed in any container and used suc-

cessfully therein without altering in any way the closure thereof, by merely removing the closure and inserting the agitator-element into the liquid.

This invention also contemplates, as a further modification, omitting the central screw-cap opening in the main closure as shown in Fig. 11, thereby leaving the closure solid and integral, with the shaft formed at its upper end into a "goose-neck" as in Fig. 7, and abutting into contact with the underside of the integral closure. In this case, however, the goose-neck is tapered and thinned from the apex of the right angle on out to the end, as shown in Fig. 11, instead of being tapered back on the shaft beyond the right-angle bend, as in Fig. 7. By removing the closure and hooking the ring-handle 7^a, which has been removed from the post 3^a for the purpose, onto the goose-neck of the shaft 4^b, in the position shown in dotted lines in Fig. 11, the agitator can be efficiently and easily operated. The improved and advantageous screw-pump container of this modification thus enables the agitator-head to be placed and used in any container without altering the closure thereof.

By means of the container of the present invention, the mixing of paints and other compound liquids can be accomplished thoroughly and quickly, and then the necessary parts can be removed for painting without any danger of the usual spilling and waste of the contents and soiling of the operator and surroundings. There are few manipulations required and these can all be performed with one hand. So simple and efficient is the container that all these advantages are obtained without raising the retail price of the container appreciably above that of the subsistent types of non-mixing container, decreasing the cost of manufacture being one of the main results of the invention.

I claim:

1. A paint mixer comprising a container having an agitator in two parts and a closure in two parts, one of said closure parts having a formation for positioning one agitator part inside the container, the other closure part having a formation for positioning the second agitator-part on the outside of the container juxtaposition with the first agitator part.

2. A paint mixer comprising a container having an agitator in two parts and a closure in two parts, one of said closure parts engaging with the container by an interior jamb fit and having a formation therein on its inner side for positioning one of the agitator parts in the container and having a central formation on its outer side, the other closure part having a formation for fitting around said central formation on the first closure part and having a formation on its periphery for holding said other agitator part thereagainst by its periphery.

3. A paint mixer comprising a container having an agitator in two parts and a closure in two parts, one of said closure parts engaging with the container by an interior 5 jamb fit and having a formation therein for positioning one of the agitator parts in the container and a central formation on its outer side, the other closure-part having a formation for fitting around said central 10 formation on the first closure part and having a formation on its outer periphery for holding said other agitator part thereagainst by its inner periphery, said agitator parts being mutually interengageable to operate the 15 agitator.

4. A mixing container, comprising a container-body, an integral, friction-type closure therefor having a centrally disposed protuberance on its outer side, an agitating element, a shaft attached to said agitating element and extending vertically into abutment with the underside of said closure, said shaft having its upper end thinned to a considerable degree and bent at right angles to the 25 shaft, and on the closure, engaging around the centrally disposed protuberance, a divided ring-shaped member having one end of the ring extended and provided with a mortise at its end sufficient to engage over the upper 30 end of the shaft to thereby constitute a handle for said shaft.

5. A mixing-container of the class described, comprising a container-body and an agitator element supported by the bottom 35 thereof and a closure-unit having two sections; said agitator element including a shaft having two parts, one of said shaft parts being disengageable from the other and shaped to fit on said closure around one of 40 said closure-sections with a jamb action, said shaft-part being locked to the closure thereby.

6. A mixing-container of the class described, comprising a container body, a closure therefor having a central capped aperture, and a reciprocable and oscillatable shaft within the container and projecting through said aperture and having its upper portion bent at right angles sufficiently to 50 form a crank-handle for said shaft, said crank-handle having its upper extremity flattened into a wedge of a sufficient size to engage between said closure and said container and separate said parts, and having its lower 55 end disengageably attached to a screw-pump, liquid-screw agitator-head.

7. In a mixing-container including an agitator and a closure; a sectional agitator-shaft, one of said sections being bent into a ring 60 with one end thereof extended beyond the point of contact of the arcs, said end having a wedge-shaped extremity, and in said wedge-shaped extremity a mortise-like aper-

ture; and another of said shaft sections having its upper end shaped and bent to hookingly engage within said aperture and thereby to engage with and support said other section. 65

8. In a mixing-container of the class described, a vertically-extending shaft carrying a liquid-screw agitator-head thereon, and a closure having a projection on its interior side; said projection having a portion extending horizontally a sufficient distance to engage with and support said agitator-head 70 when in a fully raised position against said closure, whereby said closure and said agitator may be lifted out of said container as a unit to leave it unencumbered to receive a 75 paint brush. 80

9. A mixing-container, comprising a closure and an agitator comprising a blade-head having a shaft passing through the closure; and on the interior of said closure, a downwardly projecting member having a portion extending horizontally sufficiently to engage with said blade-head to releasably support said agitator in a raised position against said closure, whereby said agitator may be lifted 85 out of the container by said shaft, supporting 90 thereon said closure. 95

10. In a mixing-container, a closure having two sections, one of said sections engaging over a screw-post projecting from the top face of the other section; said first closure-section having a lateral projection on its periphery; and an agitator including a shaft comprising two mutually engageable sections, the upper of said sections having a substantially circular shape of a circumference 100 sufficient to fit around said first closure-section, and having in its inner periphery, a depression of a sufficient size to fit over and engage with said lateral projection, whereby said upper shaft section is locked to the container and whereby said first closure section may be unscrewed from the container. 105

11. A mixing-container of the class described, comprising a container-body, a closure therefor having two mutually disengageable sections, and a reciprocable and oscillatable shaft having its upper end passing through an aperture in one of said closure-sections and having at its lower end an agitator-head; said shaft comprising two parts, one of said shaft-parts having screw threads at its lower end to engage with said agitator-head, and having its upper end thinned and bent into a goose-neck to engage with a complementary opening in said other shaft-part; said other shaft-part being disengageable from said first part and being shaped to fit around the other of said closure-sections with a jamb action. 110 115 120

In testimony whereof I affix my signature.
HENRY C. KIESELBACH.
